UNITED STATES PATENT OFFICE.

ADOLPH BERNSTEIN, OF NEW YORK, N. Y.

DESIGN FOR A SUSPENDER-CLASP.

SPECIFICATION forming part of Design No. 20,439, dated January 6, 1891.

Application filed November 28, 1890. Serial No. 372,938. Term of patent 7 years.

To all whom it may concern:

Be it known that I, ADOLPH BERNSTEIN, a citizen of the United States, residing at New York, in the county and State of New York, have invented and produced a new and original Design for Suspender-Clasps, of which the following is a specification and drawing.

The design is illustrated in the annexed drawing, which shows a front view of the clasp.

My design consists of the side bars A A, placed at an angle and having a cross-bar B placed at a distance from the mouth of the angle. The cross-bar has one edge provided with concavities C C and with convexities D

D, forming a depression E, and at its other edge the bar is provided with the convexities F and the spur or projecting portion G.

What I claim as new, and desire to secure by Letters Patent, is—

The design for a suspender-clasp, substantially as herein shown and described.

In testimony whereof I have hereunto set my hand in the presence of two subscribing witnesses.

ADOLPH BERNSTEIN.

Witnesses:

WM. C. HAUFF,
E. F. KASTENHUBER.
